UNITED STATES PATENT OFFICE.

JOHN THOMAS, OF CEDAR RAPIDS, IOWA.

BUCKLE.

SPECIFICATION forming part of Letters Patent No. 274,412, dated March 20, 1883.

Application filed January 15, 1883. (No model.)

To all whom it may concern:

Be it known that I, JOHN THOMAS, of Cedar Rapids, in the county of Linn and State of Iowa, have invented a new Improvement in Buckles; 5 and I do hereby declare the following, when taken in connection with accompanying drawings and the letters of reference marked thereon, to be a full, clear, and exact description of the same, and which said drawings constitute 10 part of this specification, and represent, in—

Figure 1, a front or face view of the buckle complete; Fig. 2, a longitudinal section, showing the strap attachment; Fig. 3, a perspective view of the tongue-slide detached.

15 This invention relates to an improvement in the buckle for which Letters Patent were granted to me April 4, 1882, No. 256,075. In that invention the frame consists of two sides connected at one end by a bar to which the tug 20 is attached, at the other end the two sides curved outward and connected by a bar outside the trace, combined with a tongue-slide which is of loop shape, the frame extending through the tongue-slide, one bar of the slide on the out- 25 side carrying the tongue, the bar on the inside standing forward of the tongue-bar, so that the tongue-slide may be turned forward, tipping the tongue inward and out of the way of the trace. That construction shows a loop exposed 30 at each side of the trace or strap which may be engaged with the buckle.

The object of my present invention is to construct the tongue-slide so that this exposure of the two sides may be avoided and a lighter 35 and neater appearance be given to the buckle; and it consists in the construction as herein-after described, and more particularly recited in the claim.

As in my previous patent, the frame of the 40 buckle is composed of two sides, A A, connected at their forward end by a bar, B, to which the tug C is attached, and at their other end by a bar, D, the two sides turned outward, as seen in Fig. 2, so as to bring the rear bar, D, into a 45 plane outside of the frame or tug-bar, as shown. The tongue-slide consists of a bar, E, in length substantially the width of the inside of the frame, and so as to stand free between the two sides, as seen in Fig. 1. On the forward edge

of this bar, and at each end, is a lug, a, projecting toward each side of the frame, and so as to lie upon the outer surface of the frame, as seen in Figs. 1 and 2, and on the opposite edge of the frame, and at each end, is a lug, b, extending in the same direction as the lugs a, but distant therefrom greater than the thickness of the frame, and so as to lie upon the inside of the frame, as seen in Fig. 2, and stand forward of the lugs a. On the outside of the bar E is a stud, d, which forms the tongue to engage 60 the trace or strap, as seen in broken lines, Fig. 2. This construction dispenses with the connection outside the frame in my previous patent and simplifies the construction of the slide. It is placed upon the frame, as seen in Fig. 1, 65 and when so placed is ready for use. To adjust the trace the slide is turned forward, as seen in broken lines, Fig. 2, which brings the tongue out of the way of the trace, and when the trace or strap is properly adjusted, then the 70 slide is returned to bring the tongue into proper position for engagement. By this construction I not only simplify the construction of the tongue-slide, but make it more convenient for manipulation, and dispense with the exposed 75 outside connections around the frame.

I do not claim, broadly, a buckle provided with a slide having a stationary tongue arranged thereon to enter the trace or strap and be drawn toward the stationary bar of the frame, 80 as such, I am aware, is not new; but

What I do claim is—

The herein-described buckle, consisting of the frame A A B D, the sides curved outward at the rear end, combined with the tongue-slide 85 E, constructed with the stud d, its two ends with lugs a a on the one edge and b b on the opposite edge, the said lugs distant from each other greater than the thickness of the frame, the said lugs a a on one edge resting upon the 90 outside of the two sides of the frame, and the other lugs, b b, upon the back side of the frame, substantially as described.

JOHN THOMAS.
